(57) **CLAIM**

The ornamental design for a barrier post with folding feet, as shown and described.

DESCRIPTION

FIG. 1 is a perspective view of a barrier post with folding feet showing my new design with the feet in a fully extended position.

FIG. 2 is a perspective view thereof with the feet in a partially extended position; and,

FIG. 3 is a top plan view thereof with the feet in a retracted position.

1 Claim, 3 Drawing Sheets

FIG. 1

FIG. 2

FIG. 3
